ABSTRACT OF THE DISCLOSURE

It is disclosed that alkyl aluminum and alkali metal halides form stable 2:1 complexes wherein the alkyl groups of the alkyl aluminum have from about 6 to about 20 carbon atoms each. Processes are disclosed whereby the compositions of the present invention are produced. Similar 2:1 complexes of such alkyl aluminum and other complexing agents are disclosed.

BACKGROUND OF THE INVENTION

Field of the invention

This invention relates to the preparation of complexes of aluminum alkyls with alkali metal halides and related complexing agents. The molar ratio of aluminum alkyls in the complexes relative to the alkali metal halide type of materials is about 2:1 on a molecular basis.

Description of the prior art

Complexes of triethyl aluminum and alkali metal halides are described in U.S. Pat. 3,415,862 wherein 1:1 molecular ratio complexes are reacted with mixtures of olefins and triethyl aluminum to form 2:1 complexes for the purpose of removing the triethyl aluminum from the olefins. Another example of prior art in this area is Annalen der Chemie, vol. 629, Nos. 1-3, March 1960, p. 34, lines 6-8, wherein it is stated that complexes containing aluminum trialkyl (C_nH_{2n+1})₃Al are detectable where n is equal to 4 but that above $n=6$ the complexes are unstable. Further art in the area is U.S. Pat. 3,317,570 wherein aluminum alkyl complexes are used in chain growth and displacement operations. Although U.S. Pat. 3,317,570 might appear to be questionable in view of the teachings of the Annalen der Chemie article, or vice versa, it is pointed out that the effluent from a chain growth process does not normally contain three higher alkyl groups having six or more carbon atoms each per aluminum molecule since many of the alkyl groups in such mixtures are ethyl or butyl; or, in appropriate circumstances, propyl. Thus, while U.S. Pat. 3,317,570 may not be directly contradicted by the Annalen der Chemie article, neither is it a teaching with regard to complexes of trialkyl aluminum compounds wherein all of the alkyl groups are hexyl or higher.

SUMMARY OF THE INVENTION

The present invention relates to a process for preparing 2:1 molar ratio complexes of alkyl aluminum whose alkyl groups have from about 6 to about 20 carbon atoms each with MX wherein M is alkali metal or tetraalkyl ammonium and X is halogen, cyanate, cyanide, azide, phenoxy or methoxy. In the process the trialkyl aluminum and the MX are heated together in molar proportions of about 2:1, respectively, at a temperature of from about 100 to about 175° C. for a period of time of from about 30 minutes to about 6 hours.

In a preferred aspect, the present process is performed at a temperature of from about 125 to about 150° C., more preferably from about 140 to about 150° C.

In a preferred aspect, the process of the present invention is conducted for a period of time of from about 1 to about 3 hours.

The present invention also relates specifically to the 2:1 molar complexes of alkyl aluminum with MX wherein in each alkyl group of the aluminum has from about 6 to about 20 carbon atoms and wherein M is alkali metal or tetraalkyl ammonium with each alkyl group having up to about 8 carbon atoms and X is fluorine or cyanide.

10 In preferred aspects of the present compositions, M of the complexes is sodium or potassium and X of the complexes is fluorine or cyanide.

The present invention also relates to a process for utilizing the aluminum alkyl alkali metal halide and related

15 complexes of the present invention wherein complexes having dissimilar alkyl groups or a different distribution of similar alkyl groups are mixed in selected proportions to provide the desired distribution of alkyl groups in the product at a temperature from about 100 to about 175° C.

20 for a time from about 30 minutes to about 6 hours. Although trialkyl aluminum reactants are preferred, other suitable reactants include dialkyl aluminum halides (F, Cl, Br, I), dialkyl aluminum alkoxides (CH_3O- through $C_{18}H_{37}O-$) and dialkyl aluminum hydrides.

25

DISCUSSION

Complexes of aluminum alkyls with alkali metal halides and related complexing agents are useful intermediates in chemical synthesis operations, for example, in the preparation of olefins by chain growth with ethylene and a lower trialkyl aluminum compound or in the separation of olefins from aluminum alkyl compounds having boiling points similar to those of the olefins. Such operations are discussed in several instances in the prior art as involving the formation and cleavage of 2:1 complexes to liberate trialkyl aluminum producing 1:1 complexes which can be recycled to reform 2:1 complexes picking up additional trialkyl aluminum. Such processes suffer from several disadvantages, particularly the severe conditions required for conversion of the 2:1 complex into the 1:1 complex. These severe conditions are conducive to the occurrence of side reactions producing undesired by-products and losses of desired materials. A feature of the present invention is that it does not involve the conversion of complexes from one molecular ratio to another but rather in all instances, the complexes are treated under conditions which retain the 2:1 molecular ratio of aluminum alkyls to alkali metal halide or related complexing agent.

50 The preferred method of producing complexes in accordance with the present invention is by direct reaction of aluminum alkyls having the desired alkyl distribution or ratio of higher alkyl groups ranging from about 6 to about 20 carbon atoms per alkyl group with the alkali metal halide or related compound, such reaction being conducted at a temperature which is sufficiently high to permit the desired reaction to take place but which is not so high as to result in significant splitting off of olefins 55 from the aluminum alkyls. In general, this requirement places a restriction of a maximum temperature of about 150° C. on the operation; however, when the reaction is conducted for brief periods of time with care to avoid localized overheating, acceptable results are obtainable at temperatures up to about 175° C.

60 Preferred compositions of matter in accordance with the present invention are of the formula 2(R_3Al):MX which designates complexes having two molecules of R_3Al per molecule of MX wherein the alkyl groups have from about 6 to about 20 carbon atoms each. The alkyl groups are straight chain or branched chain, (C_nH_{2n+1}), including cyclic, alicyclic, alkaryl, aralkyl, cycloalkyl, and like

compatible groups as well as structures in which a single alkyl group is plurally bonded to one or more aluminum molecules in polymeric or monomeric structures.

Preferred MX components in the foregoing complexes are those wherein M is alkali metal such as sodium, potassium, and lithium, or acid acting groups such as tetraalkyl ammonium wherein the alkyl groups are similar to those previously set forth for R_3Al , but preferably are straight chain having up to about 8 carbon atoms each, typically ethyl and butyl. The M constituency includes substantially single M compounds as well as mixtures such as (molar) $\frac{1}{2}$ Na- $\frac{1}{2}$ K; $\frac{1}{4}$ Na- $\frac{3}{4}$ K; $\frac{3}{4}$ Na- $\frac{1}{4}$ K, etc.

Preferred X constituency of the complexes are halogen, particularly fluorine; and cyanide. Other X constituency is alkoxy radical having from about 2 to about 30 carbon atoms, cyanate, azide, substituted amide and mixtures of two or more thereof.

Typical preferred compositions of matter in accordance with the present invention are:

- 2($n\text{-C}_8\text{H}_{17}$)₃Al:NaF
- 2($n\text{-C}_8\text{H}_{17}$)₃Al:KF
- 2($n\text{-C}_8\text{H}_{17}$)₃Al:NaN₃
- 2($n\text{-C}_8\text{H}_{17}$)₃Al:NaOCH₃
- 2($n\text{-C}_8\text{H}_{17}$)₃Al:NaCN
- 2($n\text{-C}_8\text{H}_{17}$)₃Al:NaN(CH₃)₂
- 2($n\text{-C}_8\text{H}_{17}$)₃Al:Na phenoxide
- 2($n\text{-C}_8\text{H}_{17}$)₃Al:NaOC₂H₅

Other complexes are:

- 2($n\text{-C}_8\text{H}_{17}$)₃Al:Na benzyloxide
- 2($n\text{-C}_8\text{H}_{17}$)₃Al:Na octenyloxide
- 2($n\text{-C}_8\text{H}_{17}$)₃Al:Na xylyloxide
- 2($n\text{-C}_8\text{H}_{17}$)₃Al:Na diphenyloxide
- 2($n\text{-C}_8\text{H}_{17}$)₃Al:Na heptynyloxide
- 2($n\text{-C}_8\text{H}_{17}$)₃Al:Na(4-cyclohexenyl)oxide
- 2($n\text{-C}_8\text{H}_{17}$)₃Al:Na triacontyloxide
- 2($n\text{-C}_8\text{H}_{17}$)₃Al:Na dimethylcyclohexoxide
- 2($n\text{-C}_8\text{H}_{17}$)₃Al:Na cyclohexoxide
- 2($n\text{-C}_8\text{H}_{17}$)₃Al:Na tolyloxide
- 2($n\text{-C}_8\text{H}_{17}$)₃Al:Na vinyloxide
- 2($n\text{-C}_8\text{H}_{17}$)₃Al:Na octadecoxide
- 2($n\text{-C}_8\text{H}_{17}$)₃Al:Na cumenylloxide

Other typical complexes are:

$2(\text{n-C}_8\text{H}_{17})_3\text{Al} : \begin{bmatrix} \text{NaF} \\ \text{KF} \end{bmatrix}$	$2(\text{n-C}_8\text{H}_{17})_3\text{Al} : \begin{bmatrix} \text{NaF} \\ \text{KCN} \end{bmatrix}$
$2(\text{n-C}_8\text{H}_{17})_3\text{Al} : \begin{bmatrix} \text{NaCN} \\ \text{KCN} \end{bmatrix}$	$2\text{R}_3\text{Al} : \text{NaF}$

(R=individual or mixture of two or more hydrocarbyl radicals having 6-30 carbon atoms each, average more than 6)

Other typical complexes are:

- 2($C_{18}\text{H}_{37}$)₃Al:NaF
- 2(dimethylcyclohexyl)₃Al:NaF
- 2(phenyl)₃Al:NaF
- 2(xylyl)₃Al:NaF
- 2(phenethyl)₃Al:NaF
- 2(4-cyclohexenyl)₃Al:NaF
- 2(triacontyl)₃Al:NaF
- 2(cyclohexyl)₃Al:NaF
- 2(octenyl)₃Al:NaF
- 2(tolyl)₃Al:NaF
- 2(benzyl)₃Al:NaF
- 2(cumenyl)₃Al:NaF
- 2(heptynyl)₃Al:NaF
- 2(citronnellyl)₃Al:NaF

Other typical complexes are:

- 2($C_{12}\text{H}_{25}$)₃Al:NaF
- 2($C_{14}\text{H}_{29}$)₃Al:KF
- 2($C_{16}\text{H}_{33}$)₃Al:LiF
- 2($C_{18}\text{H}_{37}$)₃Al:NaF

- 2($C_{20}\text{H}_{41}$)₃Al:KF
- 2($C_8\text{H}_{17}$)₂AlH:NaF
- 2($C_{13}\text{H}_{27}$)₃Al:LiCN
- 2($C_{15}\text{H}_{31}$)₃Al:NaCN
- 2($C_{17}\text{H}_{35}$)₃Al:KCN
- 2($C_{19}\text{H}_{39}$)₃Al:LiCN
- 2[$C_6\text{H}_{13}(C_7\text{H}_{15})_2\text{Al}$]:NaCN

Other typical complexes are:

- 10 ($n\text{-C}_6\text{H}_{13}$)₃Al:($C_{18}\text{H}_{37}$)₃Al:NaF
- 2($C_8\text{H}_{17}$)₂AlOC₂H₅:NaF
- 2($C_8\text{H}_{17}$)₃Al:($C_2\text{H}_5$)₄NF
- 2($C_{10}\text{H}_{21}$)₃Al:($C_4\text{H}_9$)₄NF
- 2($C_8\text{H}_{17}$)₂AlCl:NaF
- 15 ($C_{10}\text{H}_{21}$)₂AlCl:($C_{16}\text{H}_{37}$)₂AlCl:NaF
- 2($C_8\text{H}_{17}$)₃Al:($C_3\text{H}_7$)₄NF
- 2($C_{12}\text{H}_{25}$)₃Al:($C_2\text{H}_5$)₄NCl

The following examples indicate preferred embodiments of the present invention.

EXAMPLE I

165 millimols of tridecyl aluminum was stirred with 4.91 grams (117 millimols, 30 percent excess) of sodium fluoride for two hours at 144° C. After the stirring, 25 the mixture was cooled to room temperature and the liquid was decanted from the solid residue. The residue and decanted liquid were weighed. Residual NaF was 1.17 grams thus 3.74 grams (89 millimols) of sodium fluoride dissolved. The ratio is 165/89=1.85.

30 The product was stable when stored in a moisture-free environment.

EXAMPLE II

163 millimols of tridecyl aluminum was stirred for two 35 hours at 136° C. with 6.56 grams (134 millimols) of sodium cyanide. The mixture was allowed to cool to room temperature and the liquid was decanted. Residual NaCN was 2.44 grams thus 4.11 grams (84 millimols) of sodium cyanide dissolved during the stirring. The ratio is 40 134/84=1.94.

The product was stable when stored in a moisture-free environment.

EXAMPLE III

45 82.49 grams, 303 millimols of trihexyl aluminum was stirred for three hours at 145-155° C. with 6.3 grams, 155 mols of sodium fluoride. Substantially all the NaF dissolved and a clear solution resulted. On standing overnight at room temperature, no appreciable amount of 50 solids precipitated.

I claim:

1. The process of preparing a 2:1 molar ratio complex of trialkyl aluminum in which each alkyl group has from 55 6 to about 20 carbon atoms with sodium fluoride which comprises heating the trialkyl aluminum and the sodium fluoride in molar proportions of about 2:1 at a temperature of from about 100 to about 175° C. for a period of time of from about 30 minutes to about 6 hours, thereby preparing said complex.

60 2. The 2:1 molar complex of trialkyl aluminum with sodium fluoride wherein each alkyl group of the trialkyl aluminum has from 6 to about 20 carbon atoms.

3. A complex of the formula $2\text{R}_3\text{Al}:\text{NaF}$ wherein R is an individual or mixture of two or more alkyl radicals 65 having 6-30 carbon atoms each and averaging more than 6 carbon atoms.

4. The process of claim 1 wherein the temperature is from about 125 to about 150° C.

5. The process of claim 1 wherein the temperature 70 is from about 140 to about 150° C.

6. The process of claim 1 wherein the time is from about one to about three hours.

7. The process of making 2:1 molar complexes of trialkyl aluminum with sodium fluoride, said complexes 75 being characterized by having two or more different alkyl

groups on the aluminum which comprises, forming two or more dissimilar complexes which together have the distribution of alkyl groups desired in the product and mixing said complexes at a temperature from about 100 to about 175° C. for a time from about 30 minutes to about 6 hours.
